UNITED STATES PATENT OFFICE.

FERDINAND BURCHARTZ, OF NEW YORK, N. Y.

FLOORING.

No. 875,318.

Specification of Letters Patent.

Patented Dec. 31, 1907.

Application filed May 25, 1907. Serial No. 375,757.

To all whom it may concern:

Be it known that I, FERDINAND BURCHARTZ, a subject of the Emperor of Germany, residing in the borough of Manhattan, 5 city, county, and State of New York, have invented certain new and useful Improvements in Floorings, of which the following is a specification.

My invention relates to fireproof flooring 10 and has for its object to improve and lighten the construction thereof, without sacrificing strength and stability.

My invention will be fully described herein-after and the features of novelty will be 15 pointed out in the appended claims.

Reference is to be had to the accompanying drawings in which

Figure 1 is a plan view of my improved flooring; Fig. 2 is a sectional view thereof, 20 Fig. 3 is a detail view of one of the sections and Fig. 4 is a sectional view of a slightly different form of my invention.

My improved flooring comprises blocks A, 25 each of which is composed of tubular sections B. In the particular construction shown, four sections are employed. The sections are fitted together to form a polygon block, their open ends being in engagement with each other, and to enable the sections to fit 30 properly their ends are cut on the bias, so that the sections are wedge-shaped. The longitudinal axes of adjacent tubular sections are arranged at an angle to each other, and the cavities or recesses of the sections 35 form together an annular chamber E within the block.

It will be seen that the sections are fitted together at the corners and along radial surfaces, but the vertical walls which form the 40 outer surface of the block are continuous or unbroken. The axes of the cavities are parallel to the adjacent portions of the block's outline or perimeter, and are also parallel to the closed top and bottom walls of each section. 45 By adopting straight tubular units as sections, I am enabled to make the sections by pressure through a suitable die, thus employing a very cheap process of manufacture. The particular arrangement of the joints of 50 these sections enables me to have a continuous imperforate outer wall for each section, thus obtaining a very strong block, notwithstanding its sectional construction.

Each section is provided at its lower portion 55 with an outwardly extending flange C, the flanges of adjacent sections abutting

against each other so as to form a continuous ledge along the outer edge of the block, as shown in Fig. 1. The flanges C of adjoining blocks are also in engagement with each other as shown in Figs. 2 and 4, and thus in a complete floor, intersecting channels F are formed between the blocks, and these channels, which are open at the top, may readily have rods F' laid in them from above while 60 the blocks are supported on a suitable flat surface. The sections may be held together temporarily by tie wires B' or other holding devices, but this is not necessary. The rods F' having been secured in the walls of the 65 building, cement H is poured into the channels F so as to fill them and form a continuous course around each of the blocks A, thus 70 securely holding the sections B together. To properly position the rods F' within the 75 channels F, I may employ metal loops G, but these are not essential.

The lower surface of the floor thus formed consists entirely of brick or tile sections, and is perfectly fire-proof. The tie-rods F' are 80 located near the bottom of the block A (and the flanges C can be made very thin) so that the strength of the floor is very great.

At the center of each block I prefer to provide a recess or chamber open at the top. 85 For this purpose, the inner ends of the sections B are made with bottom flanges D, abutting as shown in Fig. 1 when the sections are put together, and forming a bottom to a central recess left between the vertical 90 inner walls of the sections. This recess is filled with cement H', thus forming as it were a central anchor to hold the sections together. The provision of the central opening or recess greatly facilitates the insertion 95 of wiring, piping, etc., at this point. In such a case only the flanges D would have to be drilled for the passage of the wires, pipes, etc., then such wires, etc. would be inserted, and finally the cement H' would be poured 100 in so as to cause the pipes, etc. to become embedded therein.

In case of the tie-rods F' bending owing to heavy loads, the flanges D will hold the rods against breaking loose from the cement, not 105 only along two parallel sides of the blocks, but at the entire perimeter. The flanges C, D, may be rounded and thickened upwardly as shown, to give them greater strength, while the bottom walls of the chambers E 110 may be made comparatively thin so as to reduce the weight of the blocks.

An important advantage of the sectional construction described is that it enables me to make comparatively large blocks from sections of moderate cross-section such as are 5 easily made on machines of the available size.

In some cases (see Fig. 4) the cement is made to cover the upper surface of the blocks A.

10 I desire it to be understood that my invention is also applicable to ceilings, and that the term "floor" used in the claims covers ceilings as equivalents.

I claim as my invention:

15 1. A floor comprising blocks composed of open-end tubular sections, each having its end surfaces on the bias, adjacent sections being arranged with their longitudinal axes at an angle to each other and with their open 20 ends in engagement, the tubular recesses of the several sections forming together an annular chamber.

2. A floor comprising blocks composed of substantially straight tubular sections set together 25 at an angle to each other with their cavities or recesses registering to form a continuous-annular chamber.

3. A floor comprising blocks composed of wedge-shaped sections, each section being a 30 tube whose axis is parallel to the closed top and bottom surfaces of the block, said sections being fitted together end to end and forming, around the center of the block, a ring-shaped chamber or space having closed 35 walls.

4. A floor comprising blocks composed of tubular sections set together with their open 40 ends in engagement along surfaces directed toward the center of the block, the communicating recesses or cavities of said sections forming an annular chamber in the block.

5. A floor comprising blocks composed of tubular sections set together with their open 45 ends in engagement along radial surfaces, the recesses or cavities of said sections forming together an annular chamber in the block, each section being provided upon the side nearest the center of the block, with a flange abutting against like flanges of the 50 neighboring sections and forming therewith the bottom to a central space between the sections.

6. A floor comprising blocks composed of tubular sections set together with their open 55 ends in engagement along radial surfaces, the recesses or cavities of the several sections forming together an annular chamber in the block, and the inner walls of the sections being spaced from each other to leave 60 a recess at the center of the block.

7. A floor comprising blocks having an 65 annular internal chamber with closed top and bottom walls and a recess in the upper surface of the block, at the central portion thereof.

8. A floor comprising blocks composed of tubular sections set together with their open 70 ends in engagement, the tube axes of all sections of the same block lying in the same plane, and the recesses or cavities of the several sections forming together an annular chamber in the block.

9. A floor comprising blocks composed of tubular sections set together with their open 75 ends in engagement, the tube axes of all sections of the same block lying in the same plane, and the recesses or cavities of the several sections forming together an annular chamber in the block, and the inner walls of the sections being spaced from each other to leave a recess at the center of the block.

10. A floor comprising blocks composed of tubular sections set together with their open 80 ends in engagement, the tube axes of all sections of the same block lying in the same plane, and the recesses or cavities of the several sections forming together an annular chamber in the block, the inner walls of the sections being spaced from each other to leave a recess at the center of the block, and the outer walls being provided with outwardly extending flanges.

11. A floor comprising blocks composed of sections fitted together along radial surfaces to form a polygonal figure, and having their 95 walls spaced at the center of the block to form a central recess, and binding material around the edges of the blocks and in the central recesses thereof.

12. A floor comprising blocks composed of 100 tubular sections set together along radial surfaces to form a polygonal figure with their cavities or recesses registering to form an internal annular chamber, each of said sections having an inwardly-extending flange 105 at the central portion of the block, and an outwardly-extending flange at the outer edge of the block, the inner flanges forming together a bottom for a central space or recess in the block, and the outer flanges forming 110 together a bottom for channels surrounding the block and adapted to be filled with binding material.

13. A floor comprising blocks composed of sections fitted together along radial surfaces 115 to form a polygonal figure, each section extending from the central portion of the block to the outer portion thereof, and having a continuous imperforate wall at the outer portion of the block, the inner portions of the 120 sections being spaced to form a recess at the center of the block for the reception of binding material to firmly connect the sections at the center.

14. A floor comprising blocks composed of 125 tubular sections fitted together end to end along radial surfaces to form a polygonal figure, with their cavities forming an annular chamber in the block, each section extending from the central portion of the block to the 130

outer portion thereof, the inner portions of the sections being spaced to form a recess at the center of the block for the reception of binding material, and the outer walls of the 5 sections, at the edge of the block, being continuous and imperforate.

15. A floor comprising blocks composed of wedge-shaped sections fitted together along surfaces converging toward the center of the 0 block, the inner walls of said sections being

spaced from each other so as to leave, at the center of the block, a recess for the reception of a connecting or binding material.

In testimony whereof I have hereunto set my hand and seal in the presence of two sub- 15 scribing witnesses this 21st day of May, 1907.

FERDINAND BURCHARTZ. [L. s.]
